(57) **CLAIM**

I claim the ornamental design for a ring, as shown and described.

DESCRIPTION

FIG. 1 is a perspective view of a ring.

FIG. 2 is a rear view of the ring of FIG. 1.

FIG. 3 is a front view of the ring of FIG. 1.

FIG. 4 is a right side view of the ring of FIG. 1.

FIG. 5 is a left side view of the ring of FIG. 1.

FIG. 6 is a top view of the ring of FIG. 1.

FIG. 7 is a bottom view of the ring of FIG. 1; and,

FIG. 8 is a perspective view of the ring of FIG. 1 in an opened configuration.

The broken lines shown in the drawings depict portions of the ring that form no part of the claimed design.
